FIG. 4

UNITED STATES PATENT OFFICE.

CHARLES POTTER, OF DONORA, PENNSYLVANIA.

DUST-PROOF FILE FOR PRINTS.

No. 895,039.

Specification of Letters Patent.

Patented Aug. 4, 1908.

Application filed May 25, 1908. Serial No. 434,807.

To all whom it may concern:

Be it known that I, CHARLES POTTER, a citizen of the United States, residing at Donora, in the county of Washington and State of Pennsylvania, have invented certain new and useful Improvements in Dust-Proof Files for Prints, of which the following is a specification.

My invention relates to filing cases and particularly to devices for filing prints, drawings, and the like.

The object of my invention is to provide a filing case for prints which will contain divisions or compartments separated from each other and easily accessible.

A further object is to provide a filing device which will be compact and dust proof.

A still further object of my invention is to provide a filing device which may be added to as desired.

Other objects will appear hereinafter from the description of my device.

In the accompanying drawings which form part of this specification: Figure 1 is a perspective view of my assembled device. Fig. 2 is a cross sectional view, somewhat diagrammatical to illustrate the course or direction of the fabric upon the frames. Fig. 3 is a plan view showing how the three sizes of frames intermesh. Fig. 4 is a fragmentary view illustrating a convenient means for supporting the opened files.

Referring again to the drawings for a detailed description of my invention: A base 1 has superimposed thereon a series of frames 2^a, 2^b, 2^c, which are all practically similar with the exception that the frames 2^b are provided with end pieces 2^{b'} to allow the adjacent frames 2^a to mesh therein as shown in Fig. 1, and the frames 2^c are provided with end pieces 2^{c'} to allow the adjacent end pieces 2^{b'} of the frames 2^b to mesh therewith, thus providing dust proof joints at the ends of the series of frames. A strip of cloth or other flexible fabric 3, preferably the exact width of the opening between the ends of the frames so as to exclude dust, is passed, as shown diagrammatically, in Fig. 2, under, up and over each side piece of each superimposed frame, one end of said fabric being attached to the base at 3^a and the other end thereof being attached to the uppermost frame at 3^b. Especial attention is called to the manner of winding this fabric 3 upon the frames. By looking at Fig. 3 it will be seen that the fabric starting from the base 1 passes under, up and

over the left hand side piece of the frame 2^a, thence across the frame and under, up and over the right hand side piece of the same frame, thence across again to the left hand side where it passes under, up and over the side piece of the frame next above and proceeds in like manner with each successive frame, so that each side piece, both right and left hand side, of each frame is embraced by said fabric. It will be therefore seen that the four frames shown in Fig. 2 provide seven files or compartments, that is, one less than twice as many compartments as there are frames, each compartment separated from the adjacent one by the single thickness of the fabric, and each accessible immediately by raising the appropriate end of the frame, as shown in dotted outline in said Fig. 2.

The frames are shown slightly separated for convenience in illustrating the course of the fabric, but in practice they rest upon one another forming dust proof joints at the sides, the ends being made dust proof by the end pieces 2^{b'} and 2^{c'} as described above. The flexibility and stretch of the fabric allow enough sag to permit of the reception of the prints or other objects 4 and the capacity of each compartment is not even limited by the thickness of the frames.

Convenient screw eyes 5 are inserted in the side pieces of the frames for convenience in lifting and a chain 6 passing over a suspended pulley 7 may be provided with a hook 8 engaging said screw eyes 5. A handle 9 attached to said chain may be provided with a hook or spur 10 for engaging a loop in said chain 6 to hold the lifted end of the file in suspension when desired.

For convenience in opening the file I prefer to provide rods 11 which pass through the projecting ends of the frames 2^a and project as shown in Figs. 1 and 3 and engage with suitable notches 12 in the end pieces 2^{b'} and 2^{c'} which together serve as hinges for the several frames when it is desired to gain access to the compartments thereof.

Having thus fully described my invention, I claim as new and desire to protect by Letters Patent of the United States:

1. In a filing device, the combination with a base, of a pile of superimposed frames, and a continuous fabric passing from the base successively under, up, and over the opposite sides of each frame to the top of said pile.

2. In a dust proof filing device, the combination of a plurality of superimposed frames,

and a single strip of fabric interlaced through successive frames in such manner as to embrace both sides of each frame, substantially as described.

- 5 3. In a dust proof filing device, the combination with a base, of a plurality of superimposed frames, end pieces on some of said frames, a single continuous fabric interlacing through successive frames and embracing both sides of each frame to form compartments whose number shall equal twice the number of the frames less one.
- 10 4. In a dust proof filing device, the combination of a plurality of superimposed frames,

end pieces on some of said frames, a single 15 continuous fabric interlacing through successive frames and embracing both sides of each frame, rods projecting from some of said frames to engage notches in adjacent end pieces, and means for selectively raising 20 either side of any frame, for the purpose set forth.

In testimony whereof I have affixed my signature in presence of two witnesses.

CHARLES POTTER.
